DYNAMOELECTRIC MACHINE END FRAME

Fredrick J. Armstrong, Fort Wayne, Ind., assignor
to General Electric Company, a corporation of
New York

Filed June 2, 1966, Ser. No. 2,513

Term of patent 14 years

(Cl. D26—5)

FIGURE 1 is an end view of a dynamoelectric machine end frame employing the new design;

FIGURE 2 is a side elevational view of the end frame as seen from the right of FIGURE 1;

FIGURE 3 is a plan view of the end frame as seen from the top of FIGURE 1; and

FIGURE 4 is a plan view of the end frame as seen from the bottom of FIGURE 1.

The view of the end frame as seen from the left of FIGURE 1 is not shown, the end frame having substantially the same appearance as that illustrated in FIGURE 2.

I claim:

The ornamental design for a dynamoelectric machine end frame, substantially as shown and described.
